VALVE ASSEMBLY

Milton A. Powers, Detroit, Mich., assignor to The
Timken Silent Automatic Company, Detroit,
Mich., a corporation of Michigan

Application April 28, 1930, Serial No. 448,131

5 Claims. (Cl. 137—139)

This invention relates to improvements in valve assemblies comprising a plurality of valve units and has particular reference to improved means for actuating said units.

5 The invention, while capable of many and diversified uses, finds particular utility when used in connection with fluid burner systems for controlling the flow of fuel from the supply side of the system to the distributing side thereof and has 10 as one of its principal objects to provide an efficient, compact and unitary valve assembly for accomplishing the above purpose which lends itself to economical manufacture owing to the comparatively few parts involved and to the 15 expedient manner in which the same may be assembled and installed.

A further advantageous feature of this invention which contributes materially to the reduction 20 in cost of manufacture and to the efficiency thereof resides in the provision of a valve assembly comprising a series of valve members cooperating to control communication from the fluid supply side of the system to the distributing side thereof together with means for simultaneously 25 and automatically actuating the valve members.

With the foregoing as well as other objects in view, the invention resides in the peculiar construction of the valve assembly and the actuating means therefor which will be made more apparent 30 as this description proceeds, especially when considered in connection with the accompanying drawing, wherein:

Figure 1 is a diagrammatic view illustrating a fuel burner system with which my improved 35 valve assembly is adapted to be used.

Figure 2 is a sectional view through a valve assembly constructed in accordance with this invention, and

Figure 3 is a sectional view taken on the line 40 3—3 of Figure 2.

Referring now to the drawing, it will be noted that there is illustrated diagrammatically in Figure 1 a liquid fuel burner system of the gravity feed type including a burner 10 driven by a suitable electric motor 11 and communicating with a fluid supply reservoir 12 by means of a supply conduit 13 and a distributing conduit 14. The outlet for the liquid in the reservoir 12 is preferably positioned above the fluid inlet to the 45 burner 10 with the result that the fluid in the reservoir flows to the burner by gravity.

In fluid burner systems of the type specified above, it is highly essential that means be provided for closing communication between the fluid 55 reservoir and burner when operation of the latter

is discontinued or, in other words, when the circuit to the electric motor 11 is broken. The foregoing is accomplished in the present instance by providing a unitary valve assembly 15 comprising generally a plurality, herein shown for the purpose of illustration as two, valve members 16 and 17 normally urged to a position wherein communication between the fluid reservoir and burner is closed by the action of gravity. The valve assembly 15 is further provided with electro-magnetic means 18 connected to the electric circuit to the motor so as to be controlled thereby and arranged in the assembly above the valve members 16 and 17 for moving the same to open position wherein communication between the reservoir 12 and burner 11 is established. The arrangement is such that upon breaking the circuit to the motor 11, the electro-magnetic means 18 is immediately de-energized permitting the valve members 16 and 17 to move under the action of gravity to the positions illustrated in Figure 2 wherein communication between the fluid supply and distributing lines is closed. On the other hand, when the circuit to the motor is closed, the electro-magnetic means 18 is energized and is of sufficient strength 60 to immediately and simultaneously move the valve members 16 and 17 to their uppermost position wherein communication between the reservoir 12 and burner 11 is established. By controlling 65 communication from the reservoir to the burner 70 with at least two valve members, as specified above, flooding of the system is eliminated since, if for any reason the valve member 16 does not seat properly, the fluid escaping thereby will be prevented from flowing into the distributing 75 conduit by the valve member 17.

In detail, my improved valve assembly, as shown in Figure 2, comprises a body portion 20 preferably cast in one piece and provided with inlet and outlet openings 21 and 22, respectively, communicating with the fluid supply and distributing conduits 13 and 14. The body portion 20 is further formed with a pair of spaced chambers 23 and 24 respectively communicating with the inlet and outlet openings 21 and 22 and with each other 80 by means of a passage 25 also formed in the body portion 20. Arranged within the chambers 23 and 24 intermediate the ends thereof are suitable valve seat members 26 and 27, respectively, having restricted passages 28 and 29 there-through establishing communication between the lower portions of the chambers and the upper portions thereof.

As shown particularly in Figure 2 of the drawing, the valve seat member 26 is disposed within 85

the chamber 23 above the inlet opening 21 and below the point of communication between the chamber 23 and passage 25. The valve seat member 27, on the other hand, is arranged within the 5 chamber 24 above the point of communication between the passage 25 and chamber 24 and below the outlet opening 22. The arrangement is such as to compel fluid flowing into the valve assembly to pass upwardly through both of the valve seat 10 members permitting any foreign matter carried by the fluid to deposit upon the bottom walls of the chambers and thereby minimize the tendency of foreign matter to accumulate upon valve seats.

As previously specified, the flow of fluid through 15 the valve assembly is controlled by the gravity seating valve members 16 and 17. As will be apparent from Figure 2 of the drawing, the valve members 16 and 17 are mounted for sliding movement within the chambers 23 and 24 longitudinally thereof and are provided with tapered lower end portions or valve members, for engaging the seat members 26 and 27 to seal the passages 28 and 29 therethrough. Both of the valve members 16 and 17 are of sufficient width to insure a tight 20 sealing engagement between the tapered end portions thereof and the valve seat members without the assistance of springs or similar means. The upper portions of valve members 16 and 17 constitute valve actuating elements and are accurately guided into engagement with the seat members by means of tubular guides 30 having the lower ends thereof sleeved within the chambers 23 and 24 and having closed upper ends projecting 25 above the body portion 20.

Referring now more in detail to the electromagnetic device 18 for simultaneously actuating the valve members 16 and 17, it will be observed from Figure 2 that this device comprises a pair of coils 33 and 34 electrically connected in series 30 by means of a conductor 35. The two are thus ordinarily connected in parallel with the motor circuit to insure simultaneous operation of valves and motor. Still referring to Figure 2, the coils 33 and 34 surround the magnetic valve members 16 and 17, respectively, which, like the end plates 37 and 38, are preferably made of material of high magnetic permeability. The plates extend 35 across the ends of both coils to reduce flux leakage. Cup-shaped members 41 and 42, also preferably made of magnetic material, are suitably secured to the plate 37 and closely embrace the upper ends of tubular valve guides 30 and effectively shorten the air gap between plate 37 and members 16 and 17. When the motor circuit 40 is closed, the coils 33 and 34 are energized, establishing magnetic flux through a magnetic circuit common to both of the valve members 16 and 17 in which the valve member 17 forms a magnetic return for coil 33 and valve member 16 forms a 45 magnetic return for coil 34. The flux established by energizing coils 33 and 34 couples the valve members 16 and 17 together magnetically causing them to move upwardly as a unit away from the seat members 26 and 27 thereby permitting the 50 fluid to flow from the supply line 13 to the distributing line 14. The valve members 16 and 17 will remain in their uppermost positions until the circuit to the motor is opened at which time the electro-magnet 18 will be de-energized permitting 55 the valve members to move to the positions illustrated in Figure 2 under the action of gravity. Since the valve members 16 and 17 are mechanically independent of each other, upon de-energization of the electromagnetic means, they are 60 free to close independently, and if a foreign par-

80 ticle should get between one of the members and its respective valve seat the other member will nevertheless close and shut off communication between lines 13 and 14.

It is to be noted that the lower end plate 38, having a higher magnetic permeability than the valve body 20, shunts the magnetic flux substantially directly from the mid-portion of one valve member to the mid-portion of the other valve member and diverts or prevents the flux leaking through the valve tips which might cause magnetic particles to adhere to the valve tips and to interfere with the proper operation of the valves.

Particular attention is called to the novel combination of the two coils energizing a common magnetic circuit whereby the two valves are operated simultaneously with the same degree of reliability and approximately the same consumption of power as has heretofore been required for a single valve member. In illustration the two coils being connected in series across the usual 110 volt power line, have the same total characteristics as a single coil connected directly across the power line operating the conventional single valve member. The available number of 100 ampere turns is divided equally between the two coils and the coils so inserted in the single magnetic flux circuit that the forces produced by each are additive. Thus even though but one coil is located in close proximity to its valve plunger the flux from the distant coil must likewise flow through the same plunger insuring reliable operation. When one or both of the valve members is lifted from its valve seat, under the influence of coil 33 or coil 34, the effective air gap in 110 the path of the common magnetic circuit is decreased, thereby decreasing the magnetic reluctance thereof. The decrease in the magnetic reluctance will increase the magnetic force on 115 each of the valve members. This is a very desirable feature as it insures reliable operation of both valves. Should one of the valves stick when coils 33 and 34 are energized, the free valve will move upwardly, and reduce the total air gap in their common magnetic circuit, with 120 the result that a materially amplified magnetic force is applied to the valve, which may be stuck, thereby insuring operation thereof.

The magnetic valve operating means, specified 125 above, is positioned upon the top of the body portion 20 and is normally concealed by means of a suitable cover 39 of non-magnetic material removably secured in place in any suitable manner.

In order to regulate the amount of fluid discharged from the supply line to the distributing line, I provide a regulating valve 40 illustrated in Figure 3 of the drawing. As shown in this latter figure, the valve 40 is adapted to extend within the passage 25 intermediate the ends 135 thereof and preferably projects out of the body portion 20 so as to permit the same to be manually adjusted.

From the foregoing it will be apparent that 140 I have provided a magnetically operated multiple-valve unit assembly for controlling the flow of fluid from a source of supply to a point of distribution which is not only compact and simple in construction, but is also efficient and economical in operation.

While in describing the present invention particular stress has been placed upon the use of two valve members and electro-magnets in the assembly for controlling communication between 145 150

a fluid supply reservoir and a point of distribution, it should be understood that the number of valve members and magnetic actuating units therefor may be varied as found desirable for efficient operation and accordingly reservation is made to make such changes as may come within the purview of the accompanying claims.

What I claim as my invention is:

1. A unitary valve assembly comprising a plurality of laterally spaced independent valve members cooperating with each other and adapted to control communication between a source of fluid supply and a point of delivery, and means for simultaneously operating said valve members including an electro-magnet having coils corresponding in number to the valve members and associated with the latter to establish a common magnetic circuit therethrough.
2. A valve assembly comprising a plurality of valve members arranged in series with each other in a fluid supply line for independently closing communication through said line, and an electro-magnetic device comprising a plurality of coils corresponding in number to the number of valve members and located in a common magnetic circuit for actuating the valves in accordance with the flow of current through the coils.
3. In a valve mechanism, means providing a plurality of valve seats; a plurality of laterally spaced valve members mounted for movement toward and away from said valve seats; a plurality of elongated, magnetic, valve actuating elements operably connected to said valve members and mounted for synchronous movement therewith; and electro-magnetic means for causing said elements to undergo substantially simultaneous valve-member-actuating movements, comprising at least two electro-magnetic coils for establishing a series magnetic circuit through at least two of said actuating elements.
4. In a valve mechanism, means providing a pair of valve seats; a pair of laterally spaced valve members mounted for movement toward

and away from said valve seats; a pair of elongated, magnetic, valve actuating elements operably connected to said valve members and mounted for synchronous movement therewith; means for causing said elements to undergo valve-member-actuating movements, comprising a magnetizable member which is normally spaced from the ends of said actuating elements when said valve members are disposed in contact with their seats, said elements being adapted to approach said magnetizable member when they undergo valve opening movements, and means, comprising a pair of electro-magnetic coils, for causing magnetic flux to take a series path which is common to both of said actuating elements and said magnetizable member, whereby valve opening movement of either one of said actuating elements reduces the reluctance of said flux path.

5. In a valve mechanism, in sub-combination, a valve casing having a fluid passage and a plurality of valve seats communicating with said fluid passage; a plurality of valve members operably disposed in said casing and mounted for movement toward and away from said valve seats for arresting fluid flow through said passage; a plurality of elongated magnetic valve actuators operably connected to said valve members and adapted to undergo endwise, valve-member-actuating movements; a plurality of substantially cylindrical, magnetic flux producing coils corresponding in number to and surrounding said valve actuators for at least a substantial portion of their length; a highly magnetically permeable member disposed adjacent one end of said coils and extending toward said actuators for conducting magnetic flux to and from said coils and said valve actuators; and a second highly magnetically permeable member disposed at the other end of said coils and operable to conduct magnetic flux to and from said actuators and said coils.
